ROBERT P. BEVAN

BY C. S. Enoch

ATTORNEY

UNITED STATES PATENT OFFICE.

ROBERT P. BEVAN, OF MINNEAPOLIS, MINNESOTA.

PUMP-JACK.

1,365,081.

Specification of Letters Patent. Patented Jan. 11, 1921.

Application filed January 13, 1920. Serial No. 351,243.

To all whom it may concern:

Be it known that I, ROBERT P. BEVAN, a citizen of the United States, and a resident of Minneapolis, in the county of Hennepin and State of Minnesota, have invented certain new and useful Improvements in Pump-Jacks, of which the following is a specification.

One object of my invention is to provide 10 in a pump jack an improved construction that will allow the best application of the driving power to the pump.

Another object is to provide improved 15 means for inclosing the gearing so that it may be run in oil and free from dirt.

Another object is to provide an improved form of construction whereby the assembly and installation of the jack are facilitated.

With these and incidental objects in view, 20 the invention consists of certain novel features of construction and combination of parts, the essential elements of which are hereinafter described with reference to the drawing which accompanies and forms a 25 part of this specification.

In the drawing, Figure 1 is a side elevation of my improved jack as applied to a pump; Fig. 2 is an enlarged side elevation of the jack with a portion broken away; 30 Fig. 3 is a section taken on the line 3—3, Fig. 2; and Fig. 4 is a section taken on the line 4—4, Fig. 3.

As shown in the drawing, the frame comprises a gear housing 1, provided with an 35 internal boss 3 and an internal boss 4.

The interior of the housing is fashioned at 5 into an internal gear, the teeth thereof preferably being cast.

A cover plate 6 is provided for the housing, and carries two bosses 7 and 8. A stub shaft 9 is driven into the boss 3 and permanently located therein, and is journaled in the boss 7 and the set collar 10 prevents the separation of the cover from the housing.

45 The pulley shaft 11, journaled in the boss 8 is driven by the pulley 12 and drives the pinion 13 co-acting with the internal gear 5, so the rotation of the pulley 12 rotates the gear housing on the stub shaft 9 rotating in the boss 7.

The cover plate is provided with three depending legs 14, 15, and 16, which support the jack on its foundation.

50 A boss 17 carried by the cover plate 6 has driven therein a stub shaft 18 on which the

walking beam 19 is journaled at 20, a set collar 21 locating the walking beam on the shaft.

The walking beam is slotted out at 22 and the roller 23 journaled on the shaft 24 carried by the boss 4 reciprocates in the slot 22.

The opposite end of the walking beam is forked at 25 and is fashioned to receive the pump links 26 adapted to be connected with the plunger 27 of the pump 28 to which the 65 jack is applied.

It is apparent that when the power pulley is driven by any suitable means the forked end of the walking beam will move up and down, and that the up stroke will be made 70 when the roller 23 is driven from approximately point 29 to the point 30, Fig. 2, and that the down stroke will be made when the roller 23 is traveling from the point 31 to the point 32, thereby giving a slow upward 75 motion with a long leverage, and a quick downward or return motion with a short leverage.

With the construction as shown, it is possible to place the pulley on the opposite end 80 of the jack from the pump and obtain the desired ratio in lifting and return stroke, an object that is much desired in pump jacks, as it allows the placing of the jack in best relation to practically any type of pump. 85

While I have described my invention and illustrated it in one particular design, I do not wish it understood that I limit myself to this construction, as it is evident that the application of the invention may be varied 90 in many ways within the scope of the following claims.

Claims:

1. In a pump jack the combination of a gear housing having its inner perimeter 95 fashioned into an internal gear, a boss centrally positioned with respect to said internal gear, a stub shaft carried by said boss, a cover plate journaled on said stub shaft, having its face closely fitted against the open side of said housing, a boss carried by said plate, a pulley shaft journaled in said boss, a driving pulley for said shaft, a pinion driven by said shaft, and coacting with said internal gear, a shaft fixed in said housing 100 and extending at right angles to the plane of said internal gear, a boss carried by said cover, a shaft fixed in said boss and extending parallel to said last named shaft, a walking beam journaled on the shaft carried by 105

said cover plate boss and having a groove at one end thereof in which said shaft extending from the external boss of said housing reciprocates, and means carried by the other 5 end of the walking beam to attach to pump links.

2. In a pump jack the combination of a cover plate forming the frame of the jack, an internal gear associated with said cover 10 plate, a stub shaft carried by said cover plate and journaled therein and centrally held in said gear, a drive shaft journaled in said cover plate, a drive pinion driven by said shaft and coacting with said gear, a 15 stub shaft projecting exteriorly from said internal gear and at right angles to the plane thereof, a walking beam mounted for oscillating motion with respect to said cover plate frame and having a groove at one end

thereof, said groove coacting with the stub 20 shaft projecting from said gear.

3. In a pump jack the combination with a cover plate forming the frame of the jack, of an internal gear, a pinion coacting with said gear and positioned to one side of the 25 center of said gear, a walking beam mounted for oscillation in respect to said cover plate and having its center of oscillation oppositely disposed with respect to the center of said gear from said pinion, and means carried by said gear for oscillating said walking beam, the end of said walking beam opposite from the end coacting with said gear being forked and having means at the forked extremity thereof for attachment to 30 35 pump links.

ROBERT P. BEVAN.
